TELEPHONE SYSTEM

John Edward Collyer, Stoke, Coventry, England,
assignor to The General Electric Company,
Limited, London, England

Application July 6, 1937, Serial No. 152,103
In Great Britain July 29, 1936

5 Claims. (Cl. 177—380)

The present invention relates to telephone systems and more particularly to systems in which a substation connected to an automatic exchange is provided with special facilities for calling frequently wanted subscribers. With such arrangements certain predetermined numbers can be selected by a single operation.

The object of the invention is the provision of improved arrangements for sending out trains of impulses in response to the momentary depression of a single key.

Certain systems for accomplishing this purpose are known. For example, there is the type usually known as the mechanical keysender in which the impulses are created by the engagement of impulse contact springs with a rotating cam shaped so as to send a train of impulses characteristic of the key depressed. The power for driving the rotating cam is usually obtained from a wound up spring.

In another type usually known as an electrical keysender, the depression of the key operates certain marking relays the contacts of which are interconnected with the bank of a step-by-step switch which rotates at a uniform rate. Impulse trains corresponding to the key depressed are transmitted to the line wires.

The present invention belongs to the latter type and relates to an improved keysender, which is particularly suitable for use in association with public automatic exchanges. Such keysenders must be capable of accommodating a large number of codes, say 25 or 50, and of sending out codes containing a plurality of trains of impulses. The character of the impulses must be at least equal to that obtained with the dial switch usually associated with automatic telephone subscribers' instruments. The present keysender is capable of fulfilling all these requirements yet contains very little apparatus, is simple in operation, is extremely flexible and contains several novel features.

According to the present invention the depression of a key associated with the subscriber's instrument causes a step-by-step switch to take up a position characteristic of the key depressed. Bank contacts of the switch are cross connected to the bank contacts of a second step-by-step switch, which latter during rotation controls the

emission of impulse trains over the subscribers' line wires. The impulses sent out over the line wires and also for driving the above mentioned second step-by-step switch are generated by a vibrator of the freely vibrating type. The reed of this vibrator has attached to it a Swedish iron mass, which is capable of attraction by an electromagnet. Before the commencement of the train of impulses representing the first digit and between each train of impulses the electromagnet is energised so as to attract the reed and hold it stationary. When the reed is de-energised it vibrates freely at its own natural frequency (which is, say, 10 per second), the impulses generated by a contact carried by the reed being of the correct ratio of make-to-break. The circuit arrangements are such that between each train of impulses there is a fixed pause of, say, 600 milli-seconds.

In an embodiment of my invention, a subscriber's instrument is provided with a strip of, for example, twenty-five keys labelled in accordance with names or designations of frequently called subscribers. Depression of any one of these keys after removal of the subscriber's receiver causes the operation of a start relay whereupon the first step-by-step switch rotates by self-interruption to find a point in its banks marked by the depressed key. When this point is reached the second step-by-step switch commences to step under the influence of the vibrator as described above.

This second switch steps until it encounters a marking made in its banks by the first switch, when impulsive ceases for a time suitable for an interdigital pause. The switch then continues to step until second and third markings are reached, impulses being transmitted meanwhile to the line wires. When the third marking is reached, a stop relay is operated which causes cessation of impulsive and returns the second switch to a normal position. The wanted subscriber has now been called and conversation may proceed in a normal manner.

It will be seen that by this arrangement the number of impulses in a train can be varied. Furthermore, the number of trains of impulses in a code is only limited by the capacity of the second or sending switch. The usual type of step-

5 by-step switch used in automatic telephone systems, containing 25 contacts in the half circle, that is 50 contacts in the full circle, can by use of single-ended wipers be arranged to send as many as five digits in an impulse train, any or all of which may contain from one to ten impulses.

10 In one form of the invention a call lamp is provided at the keysender which glows when the sender is in use. For the correct operation of the device it is necessary that all apparatus should be in its home or normal position before sending a code. Once a key is depressed the code can be cancelled by simply replacing the receiver 15 on the switch hook, but the circuit arrangements are such that the depression of a further key will not be effective until the apparatus has all returned to a normal condition. This is indicated by the lamp ceasing to glow.

20 A keysender according to the invention, although described as for use by a subscriber having an ordinary telephone instrument, could of course be employed with equal facility by an operator situated at either a branch or a main exchange. If the operator is employed in connection 25 with a private automatic branch exchange connected to a public automatic main exchange, then the keysender can be switched into use for either setting up local calls to the private exchange or junction calls to the main exchange. Connection to the latter may be established either by directly connecting the keysender to the outgoing junction lines or by switching it temporarily into a cord circuit or the like.

30 35 In order that the nature of the invention may now be better understood reference should be made to the accompanying drawing which illustrates by way of example a circuit embodying the principles of the invention.

40 45 In the drawing a number of keys 1, 2 . . . are provided, and are fitted either in the base of a subscriber's telephone instrument or in a box adjacent thereto. The remainder of the apparatus of the impulse sender consists of switches and relays, and if necessary a current supply unit 50 operating from power supply mains, and this may be fitted in a single box or cabinet near the subscriber's instrument.

55 The switch PS is the one employed to register a position corresponding to the key depressed when a call is to be made. It has four banks of contacts, and if each bank contains 25 contacts, then a maximum of 25 codes can be sent, since the switch has no normal position. The switch DS 60 which acts to control the emission of impulses, is provided with two banks only, bank DS1 being a sector whilst bank DS2 has as many groups of ten contacts as the maximum number of digits involved in any code. In switches provided with 25 contacts per row, it is usual to connect a 25-point switch in such manner that each one of a pair of contact rows is associated with a single-ended wiper, these wipers being also connected in pairs such that the equivalent of a 50-point bank is 65 produced.

70 The vibrator relay M is provided with an operating coil which when energised pulls over the iron weight MW which is fixed to a flexible spring. This action makes a contact and operates relay D, and on release of the weight, the pendulum of which it forms part emits a series of correctly spaced impulses of suitable impulse ratio until the pendulum has lost most of its energy.

75 It is proposed to describe the operation of the

device by sending a typical code. Thus if key No. 1 is depressed, earth from contact *t1* is removed from contact 5 of bank PS1 and applied to relay S which operates. It is, of course, assumed that the subscriber has previously removed the receiver, establishing a loop from the exchange through contact *k2* and the subscriber's instrument. On the operation of relay S

s1 prepares to operate relay K.

s2 energises the magnet M, pulling the weight 10 MW over and closing the associated contact.

s3 connects the magnet PSM to bank PS1 through the self-interrupting contacts *ps*.

s4 short-circuits *k1*.

s5 short-circuits *k2*.

20 The switch commences to step to find the point in its bank from which earth has been removed by key No. 1 and this continues until its wiper PS1 encounters a contact from which earth has been removed, this being caused by operation of key No. 1. All other contacts in this bank are either connected to unoperated keys or are permanently earthed. The earth for driving the 25 switch magnet being now removed, relay K operates in series with PSM from earth on *t1* via *s1*.

k1 locks relay K operated via *t1*.

k2 prepares to remove a short-circuit for the impulsive contact *d1*.

k3 operates relay C and energises the magnet DSM of the code sending switch. This switch being of the reverse drive type does 35 not yet move its wipers.

The operated key is now released, allowing relay S to return to normal.

s2 allows the weight MW of the vibrator relay to 40 release, and its contact opens and closes at a rate and ratio equal to that of the desired impulses, releasing and operating relay D.

s3 and *s4* prevent the reapplication of earth to 45 the switch bank by the restored key No. 1 from stepping the switch PS.

s5 leaves the line loop under control of the impulsive contact *d1*.

50 At the instant of opening of contact *s5*, contact *d1* is closed, but a short time later relay D releases at the commencement of the first impulse.

d1 opens the line loop.

d2 releases the magnet DSM and allows the associated wipers to take one step.

55 When relay D operates at the end of the impulse due to closure of the vibrator contacts, *d1* recloses the line loop and *d2* re-energises the magnet DSM, and the cycle is repeated. Assuming that the number corresponding to the depression of key No. 1 is 375, then the fourth contact in bank DS2 is connected to the fifth contact in bank PS2. When the magnet DSM energises for 60 the fourth time, i. e., at the end of the third impulse, earth via *k3*, *d2*, *ps1*, bank DS2, bank PS2 and contact *c1* operates relay P.

65 *p1* energises the magnet M, thereby holding the vibrator contacts closed and the relay D 70 operated.

p2 short-circuits *ps1*.

p3 de-energises relay C, which, being slugged, releases slowly.

p4 operates relay PA.

When relay C finally releases, its contact *c1* de-energises relay P which also releases slowly. When this latter action is complete,

p1 de-energises the vibrator magnet and immediately pulsing recommences.
p3 re-energises relay C.

When contact *d2* once more breaks, relay PA and the magnet DSM are both de-energised and release, and the transmission of a second impulse train is commenced. This impulse train is terminated by a second marking which is applied to the bank DS2 from bank PS3. Since the digit to be transmitted is 7, this second marking is spaced seven contacts after the first, and an inter-digital pause is provided as previously described by means of the release time of relays C and P. Impulsing is then resumed to send the final impulse train of 5, at the end of which time the wiper DS2 reaches a third marking and operates relay T via bank PS4.

t1 releases relay K.
t2 short-circuits the impulsing contact *d1*.
t3 connects the magnet DSM to bank DS1 through the contact springs *ds* which cause the switch to step its wipers by self-interruption to the first contacts in their banks.
t4 locks relay T operated to earth on wiper DS1.
k1 prepares to replace earth from *t1* on the keys.
k3 releases relay C.

The switch DS now rotates its wipers until they reach the home position, relay T remaining held until then. When stepping ceases, the circuit of relay T is broken by wiper DS1, and this relay releases, its contact *t1* finally enabling further digits to be sent if required.

It should be noticed that the lamp EL, provided to show the subscriber that the impulse sender is transmitting, lights up immediately the subscriber releases the depressed button from earth derived from wiper DS1. The lighting of this lamp warns the subscriber not to depress any further buttons nor to operate his own dial whilst the sender is impulsing. It should be noticed that two rows of terminals designated TP are provided between bank DS2 and the cooperating banks of the switch PS. These terminals form a translating panel, enabling the depression of any button to send any desired code. All the terminals on banks PS2, PS3 and PS4 are wired to appropriately labelled terminals on the panel, as also are the terminals of bank DS2. According to the digits to be sent by each key, jumper wires similar to those shown dotted are run between the two groups of terminals, this permitting easy setting up of any particular code, which may be changed to another code if circumstances require.

Should the subscriber find, midway through the emission of a code, that the wrong number is being sent, the code can be cancelled by replacing the receiver. This breaks the line loop and releases any switches taken into use at the exchange. The keysender meanwhile completes its cycle of operations before returning to normal, the "engaged" lamp EL warning the subscriber not to attempt to set up a further code.

Should he do so by depressing a key, it will be seen that since either contact *k1* or *t1* is operated, no earth is available to operate relay S, so that the storage and sending cycle cannot be

repeated until the sender is in a normal condition, with all relays released and the switch DS suitably positioned.

I claim:

1. In an impulse sender, a rotary switch, means for marking a plurality of consecutive or non-consecutive contacts in the bank of said switch, means operating at a predetermined speed, an impulse sending circuit including a contact set actuated periodically by said last means, a stepping circuit for said switch including a contact set actuated periodically and in synchronism with the actuation of said first contact set, and means operated over a wiper of said switch when said wiper encounters each marked contact, thereby to interrupt, for an interval of time, the operation of said second means and the actuation of said contact sets. 5

2. In an impulse sender, a rotary switch, means for marking a plurality of consecutive or non-consecutive contacts in the bank of said switch, means operating at a predetermined speed, an impulse sending circuit including a contact set actuated periodically by said last means, a stepping circuit for said switch including a contact set actuated periodically and in synchronism with the actuation of said first contact set, means operated over a wiper of said switch when said wiper encounters certain of said marked contacts thereby to interrupt, for a predetermined interval 20 of time, the operation of said second means and the actuation of said contact sets, and means operated over a wiper of said switch when said wiper encounters a marked contact other than said certain marked contacts thereby to render 25 said first contact set ineffective without interrupting the operation of said second means. 30

3. In an impulse sender, a rotary switch having a normal position, two stepping circuits for said switch, means for marking a plurality of consecutive or non-consecutive contacts in the bank of said switch, a member vibrating at its natural frequency, an impulsing contact in one of said circuits, said contact controlled by said member to step said switch, means operated over a wiper 40 of said switch when said wiper encounters each marked contact except the last to interrupt, for an interval of time, the vibration of said member, and means operated over said wiper when said wiper encounters said last marked contact to interrupt said one stepping circuit and to render the other stepping circuit effective, said switch thereafter operating self-interruptedly in said other circuit until it reaches its normal position. 45

4. In an impulse sender as claimed in claim 3, an impulsing circuit including a second contact controlled by said member, and means for shunting said second contact responsive to the operation of said last means. 55

5. In an impulse sender, a plurality of manually operable keys, a rotary switch, means for marking a plurality of contacts in the bank of said switch responsive to one operation of any one of said keys, an impulse generator operative responsive to a second operation of said one key and effective to rotate said switch step-by-step, and means operated over a wiper of said switch when said wiper encounters each marked contact thereby to interrupt the operation of said generator for a predetermined interval of time. 60

JOHN EDWARD COLLYER.
